DOWEL ASSEMBLY FOR PAVING JOINTS

Bengt F. Friberg, St. Louis, Mo., assignor to
 Laclede Steel Company, St. Louis, Mo., a corporation of Missouri

Application July 22, 1935, Serial No. 32,528

6 Claims. (Cl. 94—18)

It has been found to be impossible to construct a concrete pavement of any considerable extent so that it will not crack under strains caused by change in temperature or otherwise. As such cracks cannot be avoided it has been found advantageous to control their location so as to divide the pavement into predetermined sections of limited area. This may be accomplished either by completely dividing the pavement into blocks by means of expansion or contraction joints, or crack-locating means may be employed weakening the pavement along the desired lines so that when cracking occurs under strain it will follow such lines and result in a like division of the pavement into blocks. To prevent relative vertical movement of the blocks it has been customary to connect their adjacent edges by dowels extending across the actual or potential lines of division. To effectively perform their function, both when the joints or cracks are closed at high temperature and when they are opened by a decrease in temperature, such dowels must be parallel not only with the plane of the pavement but with each other. Heretofore great difficulty has been experienced in securing proper positioning of the dowels. Even if their initial location is successfully accomplished, they are likely to be displaced by the application of the concrete.

The object of my invention is to provide simple and effective means for insuring the proper positioning of the dowels, and further, to produce a unitary structure which may be put together at the side of the roadway and lifted into position as a complete assembly.

In the accompanying drawing, which illustrates one form of dowel assembly made in accordance with my invention, Figure 1 is a vertical cross-section of a part of a roadway before the concrete has been applied; Figure 2 is a top plan view of the parts shown in Figure 1; Figure 3 is an enlarged section taken on the line 3—3 of Figure 2; and Figure 4 is a section on a reduced scale, taken on the line 4—4 of Figure 2, after the concrete has been applied.

For the purposes of illustration I have shown an expansion joint 5 extending across a roadway from a side form 6, but my dowel assembly may be used in connection with various other types of crack-locating means. The joint 5 is provided with uniformly spaced openings 7 for the passage of dowels 8, the ends of which extend into the concrete 9 at each side of the joint. A pair of spacer rods 10 are located one at each side of the joint. The rods have welded to them alternately dowel engaging members in the form

of supports 11 and expansion sleeves 12. The supports 11 are each preferably made of wire in the form of a hair-pin loop, the turn of which embraces the dowel. One prong of the loop enters the soil and the other is bent out to form a ground stop at the level of the subgrade. Welded either to the rod 10 or to the support 11, or to both, is a stop 13 for limiting the endwise movement of the dowel. Each expansion sleeve 12 is provided with a closure 14 at the outer end to prevent entrance of the concrete and this is spaced at the proper distance from the end of the dowel by a wire 15. This wire is of such size as to insure correct spacing, but may be bent or crushed by the expansion of the concrete to permit the necessary telescopic movement between the dowel and the sleeve to compensate for such expansion.

To assemble the device the dowels are first centrally located in openings 7 of the expansion joint 5 and then the loops and sleeves applied to their ends. The proper location of the loops and sleeves on the dowels is insured by the stops 13 and 15. This operation may be carried out at any convenient point and the complete assembly transferred as a unit to its final location. As each dowel is engaged at both ends by members which are rigidly attached to the spacing rods, parallelism of the dowels with each other necessarily results, and the parallelism of the dowels with the plane of the pavement is insured by the supports welded to the spacer rods at the proper height from the ground stops.

As my construction includes, in one unit, the spacer rods, the supporting elements, and the expansion sleeves, it is possible to make the supporting members of exact height to fit the position to be occupied by them in the pavement and no difficulty will arise by having loose supports of different heights to be assembled or located at the construction. My construction, therefore, results in considerable saving of time as compared to the practice, heretofore common, of assembling all loose parts by tie wires on the job, and in addition, gives the very great advantage of rigidity inherent in the manufactured article.

Having fully described my invention, what I claim as new and desire to secure by Letters Patent of the United States is:

1. In a device of the class described, the combination with pavement separating means, of a plurality of dowels slidably mounted in and extending at each side of said means, a pair of spacing bars, one positioned at each side of the

- 5 pavement separating means, dowel engaging members for each end of each dowel unconnected with the separating means and welded to said bars, said members having movement on the dowels, and means for limiting the movement of the dowels in the direction of their length.
- 10 2. In a device of the class described, the combination with a plurality of dowels for connecting the adjacent edges of paving blocks, of positioning means for said dowels, said means including a spacing bar, a plurality of expansion sleeves welded to said bar and provided with closed ends, and distortable means for spacing the closed ends of the sleeves from the ends of the dowels.
- 15 3. In a device of the class described, the combination with pavement separating means, of a plurality of dowels slidably mounted in and extending at each said of said means, a pair of spacing bars one positioned at each side of said means at a substantial distance therefrom, each of said dowels engaging at one end with a spacing bar, and expansion sleeves engaging the other ends of the dowels, said expansion sleeves being unconnected with the separating means and each being permanently secured to a spacing bar.
- 20 4. In a device of the class described, the combination with pavement separating means, of a plurality of dowels slidably mounted in and extending at each side of said means, a pair of spacing bars one positioned at each side of said means at a substantial distance therefrom, each of said dowels engaging at one end with one of the spacing bars, and expansion sleeves engaging the other ends of the dowels, said expansion sleeves being unconnected with the separating means,
- 25 rating means, said expansion sleeves being permanently secured to the spacing bars alternately with the dowels.
- 30 5. In a device of the class described, the combination with pavement separating means, of a plurality of dowels extending through said means, a pair of spacing bars, one positioned at each side of said means at a substantial distance therefrom, dowel engaging means including dowel stops, and supports for the spacing bars positioned below the dowels, each of said dowel engaging means including a loop and a strap having a turned over end engaging the upper part of the periphery of the dowel, whereby said engaging means prevents twisting of the supports out of a vertical plane perpendicular to the axis of the dowel, said dowel engaging means being unconnected with the pavement separating means and rigidly secured to the spacing bars.
- 35 6. In a device of the class described, the combination with pavement separating means, of a plurality of dowels extending through said means, a pair of spacing bars, one positioned at each side of said means at a substantial distance therefrom, dowel engaging means rigidly secured to the spacing bars, and supports for the spacing bars positioned below the dowels and secured against pivotal movement relative to a dowel engaging means, said dowel engaging means contacting with the periphery of the dowel at upper and lower points so spaced in the direction of the length of the dowel that said dowel engaging means prevents twisting of the supports out of a vertical plane perpendicular to the axis of the dowel, said dowel engaging means being unconnected with the pavement separating means.

BENGT F. FRIBERG.
